(57) **CLAIM**

The ornamental design for a flashlight, as shown and described.

DESCRIPTION

FIG. 1 is a side view of a flashlight design according to the present invention;

FIG. 2 is a side view of an alternate flashlight design according to the present invention;

FIG. 3 is an enlarged right end view of the flashlight shown in FIG. 1, wherein the right end view of the flashlight shown in FIG. 2 is substantially the same as the right end view in FIG. 3;

FIG. 4 is an enlarged left end view of the flashlight shown in FIG. 1, wherein the left end view of the flashlight shown in FIG. 2 is substantially the same as the left end view in FIG. 4;

FIG. 5 is a side view of a second alternate flashlight design according to the present invention wherein the right end and left end views of the flashlight shown in FIG. 5 are substantially the same as the right end and left end views shown in FIGS. 3 and 4, respectively; and,

FIG. 6 is a side view of a third alternate flashlight design according to the present invention wherein the right end and left end views of the flashlight shown in FIG. 6 are substantially the same as the right end and left end views shown in FIGS. 3 and 4, respectively.
